DESIGN FOR A VELOCIPED

Bert J. Anderson, Hammond, Ind.

Application February 5, 1934, Serial No. 50,618

Term of patent 14 years

To all whom it may concern:

Be it known that I, BERT J. ANDERSON, a citizen of the United States, residing at Hammond, in the county of Lake, and State of Indiana, have invented a new, original, and ornamental Design for a Velocipede, of which the following is a specification, reference being had to the accompanying drawing, forming part thereof.

Figure 1 is a perspective view of the velocipede of this design.

Figure 2 is a plan view taken from the bottom, and shows in particular the two-piece frame. It is also shown that the saddle is an integral part of the front section of the frame.

I claim:

The ornamental design for a velocipede, as shown and described.

BERT J. ANDERSON.
